DESIGN FOR A HEAT APPLICATOR FOR HUMAN USE

James W. Gardner, Bremerton, Wash.

Application March 11, 1946, Serial No. 127,356

Term of patent 14 years
(Cl. D83—1)

To all whom it may concern:

Be it known that James W. Gardner, a citizen of the United States, residing at Bremerton, Washington, has invented a new, original, and ornamental Design for a Heat Applicator for Human Use, of which the following is a specification, reference being had to the accompanying drawing, forming a part thereof, in which

Fig. 1 is an end view of the front of a heat applicator for human use, showing my new design;

Fig. 2 is an end view of the rear of the heat applicator of Fig. 1;

Fig. 3 is a plan view of the heat applicator of Fig. 1; and

Fig. 4 and Fig. 5 are cross sectional views taken on lines 4—4 and 5—5, respectively, of Fig. 3.

I claim:

The ornamental design for a heat applicator for human use, as shown.

JAMES W. GARDNER.
